CHARLES HADDAD'S PATENT OFFICE.

CHARLES HADDAD OF LONG ISLAND CITY, NEW YORK, ASSIGNEE OF ONE-HALF TO
JOHN FOLZ, OF NEW YORK, N. Y.

TO CIGAR PIPE.

2,117,486

Specification of Letters Patent. Patented Nov. 24, 1914.

Application filed March 23, 1914. Serial No. 228,398.

To all whom it may concern:

Be it known that I, CHARLES HADDAD, a citizen of the United States, residing at Long Island City, in the county of Queens and State of New York, have invented certain new and useful Improvements in Tobacco-Pipes, of which the following is a specification.

My invention relates to improvements in tobacco pipes, the object of the invention being to provide a pipe of this character in which the smoke will be compelled to take a relatively long path from the bowl of the pipe to the mouth of the smoker, and during such path will be permitted to expand in a relatively long chamber so that the smoke will be cool when it reaches the mouth of the smoker.

A further object is to provide a pipe of the character stated which can be readily cleaned when the two sections of the stem are separated, as the several passages will then be readily accessible to any cleaning device.

With these and other objects in view, the invention consists in certain novel features of construction and combinations and arrangements of parts as will be more fully hereinafter described and pointed out in the claim.

In the accompanying drawings: Figure 1 is a view in longitudinal section illustrating my improved pipe, and Fig. 2 is a view in cross section on the line 2-2 of Fig. 1. 35 1 represents the bowl of the pipe and 2 an integral stem section which is connected to a removable stem section 3 by means of a metal band or collar 4.

While the invention is not limited to the particular manner of connecting the stem sections, I have illustrated a simple construction in which the band or collar 4 is secured by cement or otherwise to the stem section 2, and is screw-threaded as shown 45 at 5 to receive the screw-threaded end of section 3. To distinguish these stem sections in the description, I shall refer to the section 2 as the "bowl stem section" and the section 3 as the "mouth piece stem section."

50 While I preferably make the sections of different material, as for example, the section 2 of wood or other material commonly used in the forming of the bowl, and the section 3 of rubber, amber, horn, or other similar material ordinarily used in the mak-

ing of pipe mouth pieces, I do not limit myself to any particular material.

The sections 2 and 3 are provided with a longitudinal expansion chamber 6 which extends from a point adjacent the bowl 1 60 in section 2 to a point adjacent the free end of mouth piece section 3, and is of relatively large diameter to allow the smoke to freely expand as will hereinafter appear.

The smoke from the tobacco in bowl 1 65 passes first through a passage 7 in bowl section 2, which registers with a passage 8 in mouth piece section 3, the latter communicating with the outer end of chamber 6. The smoke from chamber 6 passes through 70 a passage 9 in bowl section 2, said passage communicating with the end of chamber 6, adjacent bowl 1, although it will be noted that a considerable space is provided at this end of the chamber so that moisture 75 may accumulate therein without blocking the smoke passage.

The passage 9 in bowl section 2 communicates with a passage 10 in mouth piece section 3, said passage extending to the extreme end of section 3 for directing the smoke in the mouth of the user.

In operation, the smoke from bowl 1 passes through passage 7-8 into the outer end of chamber 6, and then flows through 85 the chamber 6 toward the bowl and in such chamber is free to expand by reason of the relatively large diameter of said chamber. The smoke is drawn from the bowl end of chamber 6 through the passage 9-10. 80

When the pipe sections 2 and 3 are separated, the several passages and chambers can be readily cleaned out by means of the ordinary devices provided for such purpose, and the pipe may be kept in a clean and 95 sanitary condition.

Various slight changes might be made in the general form and arrangement of parts described without departing from my invention, and hence I do not limit myself to the precise details set forth, but consider myself at liberty to make such changes and alterations as fairly fall within the spirit and scope of the appended claim.

Having thus described my invention, what 105 I claim as new and desire to secure by Letters' Patent is:

A tobacco pipe, comprising a bowl having an integral stem section, a mouth piece stem section removably secured to the end of the 110

bowl stem section, said bowl and stem sections having a longitudinal expansion chamber formed in both sections, extending from the outer end of the bowl section to a point 5 adjacent the bowl and from the inner end of the mouth piece stem section to a point midway between the ends of said mouth piece stem section, said bowl stem section having a passage communicating with the bowl and with 10 a passage in the mouth piece stem section, whereby the smoke is directed from the bowl into the outer end of the expansion chamber, and said stem sections having a passage extending from the expansion chamber adjacent the bowl to the mouth piece 15

end of the mouth piece section, said expansion chamber being appreciably larger in diameter than any of said passages, said expansion chamber located between the passage leading from the bowl thereto and the 20 passage leading therefrom to the end of the mouth piece stem section, substantially as described.

In testimony whereof I have signed by name to this specification in the presence of 25 two subscribing witnesses.

CHARLES HADDAD.
